(57) **CLAIM**

The ornamental design for a curtain holder tie, as shown and described.

DESCRIPTION

FIG. 1 is a front, right, top perspective view of the curtain holder tie, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a front, right, top perspective view shown in an alternate configuration.

The dashed broken lines in the figures are for the purposes of illustrating portions of the curtain holder tie and form no part of the claimed design.
